DESCRIPTION

See application file for complete search history.

FIG. 1 is a top, front and right side perspective view of a
connector for a nasal cannula assembly embodying our new
design.

FIG. 2 is a top, rear and right side perspective view thereof.
FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

Broken lines are used to illustrate features of the nasal
cannula assembly which form no part of the claimed design.
Dash-dot lines define the bounds of the claimed design and
form no part thereof.
